Filed Aug. 28, 1970, Ser. No. 24,745

Term of patent 7 years

Int. Cl. D15—05

U.S. Cl. D49—1

FIG. 1 is a front elevational view of the laundry washer adapter;

FIG. 2 is a side elevational view of the laundry washer adapter;

FIG. 3 is a rear elevational view of the laundry washer adapter; and

FIG. 4 is a front perspective view of the laundry washer adapter.

The side opposite to that shown in FIG. 2 is a mirror image thereof.

The washer shown in broken lines in FIG. 4 is for illustrative purposes only and forms no part of the claimed design.

I claim:

The ornamental design for a laundry washer adapter, as shown and described.
